UNITED STATES PATENT OFFICE.

HERBERT ALEXANDER THOMPSON, OF NORTH SHIELDS, ENGLAND, ASSIGNOR OF ONE-HALF TO SMITH'S DOCK COMPANY LIMITED, OF SOUTH SHIELDS, ENGLAND, A CORPORATION OF GREAT BRITAIN.

CONSTRUCTION OF SPRAYING NOZZLES OR ATOMIZERS.

Application filed June 12, 1922. Serial No. 567,653.

To all whom it may concern:

Be it known that HERBERT ALEXANDER THOMPSON, engineering manager, a subject of the King of Great Britain, residing at 5 9 Cleveland Terrace, North Shields, in the county of Northumberland, England, has invented a certain new and useful Improvement in the Construction of Spraying Nozzles or Atomizers, of which the following 10 is a specification.

This invention relates to spraying nozzles or atomizers for use in dealing with liquid fuel for combustion purposes, and has for its object to provide a generally 15 improved construction of spraying nozzle or atomizer, and in particular an improved construction of that type of atomizer wherein in a spraying nozzle to which oil under pressure is supplied and flows into an annular chamber where it becomes heated or 20 superheated and expanded and then flows into a second heating chamber adjacent to the outlet orifice, in which is located a conical projection, the apex of which is presented to the outlet orifice of the nozzle, 25 the oil entering the latter chamber at an increased velocity and being subject to a whirling motion before issuing from the nozzle in the form of a fine spray.

According to the present invention, additional chambers which may be coaxial or annular are provided for the admission of steam or air to the chamber which is adjacent to the outlet orifice, whereby the 35 heavy oil is atomized or pulverized by means of the steam or air meeting the oil and rotating in the said chamber, so that complete atomizing is effected and when emitted from the outlet in the nozzle the fuel can be lighted by means of a torch in the usual way.

The discharge passages for the oil and steam or air are preferably tangential and having the outlets so disposed that separate 45 opposing or converging streams of oil and steam or air are discharged therefrom and meet upon or about the directing cone in the outlet chamber.

Suitable auxiliary apertures may be provided by which a quantity of air can be introduced by injection or induction into the burner by means of the steam blast.

The accompanying drawings illustrate several forms of the invention,

Fig. 1 is a longitudinal section through one form of the improved atomizer.

Fig. 2 is a section on line Y Y of Fig. 1.

Fig. 3 is a longitudinal section of a modified construction.

Fig. 4 is a longitudinal section of another modification, and

Fig. 5 is a section on line X X of Fig. 4.

Fig. 6 is a longitudinal section showing a further modification.

Fig. 7 is a longitudinal section of a still further modification.

Fig. 8 is a detail view of a plug for closing the central air inlet in the construction shewn in Figs. 4 to 7 when required.

The improved device shewn in Figs. 1 70 and 2 comprises a back disc or rear body *a* and a front body *b* so constructed that a recess in each of the bodies register upon assembling, and forms an annular chamber *c* from which small ducts or holes *d* lead 75 into a central chamber *e* fitted with a variable nozzle *f*.

Within this central chamber *e* is arranged a hollow directing cone *g* its hollow part forming an internal chamber *h* from 80 which also small ducts or holes *i* lead to the central chamber *e*. The holes or ducts *d* and *i* leading to the central chamber, are formed tangentially so that a swirling or rotating movement is imparted to the oil and to the 85 steam and (or) air passing to the central chamber *e*. These holes or ducts may be of any desired number and size and may be arranged at any angle or in any desired manner to obtain the necessary effect.

It will be obvious that the oil and the steam or air or steam and air, may be supplied to the annular chamber *c* or to the chamber *h* in the hollow directing cone, or vice versa as desired.

Suitable connections such as pipes *j* and *k* convey the oil and steam and (or) air to the annular chamber and the hollow directing cone, and these may be of any desired shape or design and may be provided with 100 shut-off cocks or valves for controlling the oil supply and the steam or air supply.

These control valves may be arranged either as separate connections with pipes leading to the apparatus, or if desired, they 105 may be made to form integral parts of same.

The valve controlling the oil supply and the valve controlling the steam or air sup-

ply may be so arranged that the operation of one hand wheel controls both supplies by which the quantity of steam or air passed in relation to the amount of oil burned may be automatically controlled with one regulation.

In operation oil is supplied through the oil conveying connections *k* to the annular chamber *c* and from thence passes by way 10 of the holes or ducts *d* to the central chamber *e*, whilst steam, or air, or steam and air pass from their connections *j* to the interior chamber *h* of the hollow directing cone and thence through the holes or ducts *i* to 15 the central chamber *e* where, meeting the oil with a rotating and swirling motion imparted by the tangential direction of the holes or ducts, a complete atomizing of the oil is effected and the directing cone *g* directs the fuel to the nozzle *f* from which it is emitted and ignited.

In the modification shown in Fig. 3, the annular chamber 1 is located around the directing cone behind the ducts or passages 2 25 and both said passages and the passage 3 are inclined forwardly so as to discharge into the rear end of the outlet chamber 4.

5 and 6 are cocks controlling the supply of oil and steam or air to the chambers 1 30 and 7. The operation is as before described with reference to Figs. 1 and 2.

In the modification shown in Figs. 4 and 5 an additional air intake 8 is provided through the centre of the cone 9, which is 35 fitted with a hollow plug 10 which, when it is not desired to use the additional air inlet may be replaced by a solid plug *p* such as shown in Fig. 8, which plug is provided with a projection *q* to fill in the apex of the cone 9 when the additional air inlet is not in use.

The chamber 11 is in this case also of annular form and discharges into the chamber 12 along the face of the cone 9 in a forward direction whilst the annular chamber 13 discharges centripetally through tangential slots forming the ducts or passages 14 so as to meet the discharge from the passages 15 in the chamber 12 about the cone 9.

50 In this construction the annular chamber 13 is formed between the front disc or body 16 which carries the nozzle 17, and the rear disc or body 18 and the annular chamber 11 is formed in the rear disc or body 18 around the plug 10 or *p* as the case may be, and the tangential passages 14 are in the form of slots in an annular extension *d'* from the body 18 around the cone 9. The outer ends of the slots are closed by the inner face of the front body 16. 19 and 20 indicate passages to which the supply pipes and connections are fitted.

The operation is as described with reference to Figs. 1 and 2 with the exception that 55 the streams from the passages 15 and 14

issue at different angles into the chamber 12.

The modification shown in Fig. 6 is similar in construction and operation to that shewn in Figs. 4 and 5 with the exception that an 70 annular lip *r* is provided around the cone 9 so as to direct the streams of oil and steam or air from passages 14 and 15 forwardly, before they meet in the chamber 12.

In the modification shewn in Fig. 7 the 75 construction is similar to that shewn in Figs. 4 and 5, with the addition of an auxiliary air admission chamber *s* to which air is admitted by passages *t*. This chamber *s* is formed as an extension from the front body *b* and with this arrangement the nozzle *f* of the other constructions may be omitted. According to this form the parts are precisely as in Figure 4 and are similarly indicated, except that the part 21 is enlarged at its outer portion to receive the slots *t* and the chamber *s*.

The operation of this modification is as previously described as regards the streams of oil and steam or air meeting in the 90 chamber 12, but in addition, a further supply of air may be admitted through the central passage 8 and as the already atomized fluid passes from the chamber 12 through the chamber *s* a further supply of air is drawn in by induction through the auxiliary air passages *t*.

By the novel means described practically the same effect is obtained by the meeting of the oil and steam, or air, as in the pressure atomizer described in the specification of Letters Patent No. 27324 of 1912, already referred to, with the advantage that it is not absolutely necessary to supply the oil under pump pressure, as the supply can be delivered by gravity feed, and if desired, preheating of the oil may be dispensed with.

What I claim as my invention and desire to secure by Letters Patent is:—

1. A spraying nozzle or atomizer for use 110 in dealing with liquid fuel for combustion purposes comprising the combination of a central outlet chamber, two annular supply chambers disposed coaxially, tangential discharge passages leading in converging directions from said annular supply chambers into said outlet chamber so that the jets of discharged fluid meet in said outlet chamber.

55 2. A spraying nozzle or atomizer for use in dealing with liquid fuel for combustion purposes comprising the combination of a central outlet chamber having an interchangeable nozzle and containing a directing cone facing the outlet, two annular supply chambers disposed coaxially, tangential discharge passages leading in converging directions from said annular supply chambers into said outlet chamber so that the jets of discharged fluid meet in said outlet chamber.

60 3. A spraying nozzle or atomizer for use 120

- in dealing with liquid fuel for combustion purposes comprising the combination of a central outlet chamber, two annular supply chambers, disposed coaxially, tangentially arranged discharge passages leading from said outer and inner annular chambers into said central outlet chamber, the passages leading from the outer supply chamber being disposed in a substantially radial direction in regard to the axis, and the passages from the inner annular chamber being inclined in an axial direction whereby the jets of fluids discharged from said supply chambers meet in tangential and converging directions in said outlet chamber.
4. A spraying nozzle or atomizer for use in dealing with liquid fuel for combustion purposes comprising the combination of a central outlet chamber, an annular supply chamber surrounding said outlet chamber, an inner supply chamber located coaxially with said annular supply chamber, fluid passages leading in meeting directions from said annular and inner supply chambers into said outlet chamber, whereby the respective jets of fluid are directed one into the other in said central outlet chamber and means for admitting additional air to said central chamber.
5. A spraying nozzle or atomizer for use in dealing with liquid fuel for combustion purposes comprising the combination of a central outlet chamber, two annular supply chambers disposed coaxially, discharge passages leading from said annular chambers into said outlet chamber and directed so that the jets of fluid discharged from the respective annular chambers meet in said outlet chamber, and means for admitting additional air to said central chamber.
6. A spraying nozzle or atomizer for use in dealing with liquid fuel for combustion purposes comprising the combination of a central outlet chamber, two annular supply chambers disposed coaxially, discharge passages leading from said annular chambers into said outlet chamber and directed so that the jets of fluid discharged from the respective annular chambers meet in said outlet chamber, and means for admitting additional air by induction to said central chamber.
7. A spraying nozzle or atomizer for use in dealing with liquid fuel for combustion purposes comprising the combination of a central outlet chamber, two annular supply chambers disposed coaxially, discharge passages leading from said annular chambers into said outlet chamber and directed so that the jets of fluid discharged from the respective annular chambers meet in said outlet chamber, means for admitting additional air by induction both centrally to the outlet chamber and in an annular manner around the outlet nozzle thereof.
8. A spraying nozzle or atomizer comprising the combination of disc like front and rear body parts secured together and recessed on their meeting faces to form between them a central outlet chamber, and an annular fluid supply chamber divided from said central outlet chamber by an annular partition, an annular fluid supply chamber formed by a recess in the rear body part, a directing cone formed on the face of said rear body part and located in the centre of the outlet chamber, tangentially arranged fluid passages formed in the said rear body part and through the annular partition between the annular supply chamber and the outlet chamber, said passages in the rear body part and in the annular partition being inclined in converging directions, whereby the fluids from the respective supply chambers are directed in tangential and converging directions into said outlet chamber about the directing cone.
9. A spraying nozzle or atomizer comprising the combination of disc like front and rear body parts, secured together and recessed on their meeting faces to form between them a central outlet chamber and an annular fluid supply chamber divided from said central outlet chamber by an annular partition, an annular fluid supply chamber formed by a recess in the rear body part, a directing cone formed on the face of said rear body part and located in the centre of the outlet chamber, tangentially arranged fluid passages leading from the annular supply chambers to the outlet chamber and consisting of holes in the rear body part and slots in the said annular partition, said fluid passages and slots being inclined in converging directions whereby the fluids from the respective supply chambers are directed in tangential and converging directions so as to meet in said outlet chamber about the directing cone.
10. A spraying nozzle or atomizer comprising the combination of a disc like front and rear body parts secured together and recessed on their meeting faces to form between them a central outlet chamber, and an annular fluid supply chamber divided from said central outlet chamber by an annular partition, an annular fluid supply chamber formed by a recess in the rear body part, a directing cone formed on the face of said rear body part and located in the centre of the outlet chamber, tangentially arranged fluid passages formed in the said rear body part and through the annular partition between the annular supply chamber and the outlet chamber, said passages in the rear body part and in the annular partition being inclined in converging directions, whereby the fluids from the respective supply chambers are directed in tangential and converging directions into said outlet chamber about the directing cone.

converging directions into said outlet chamber about the directing cone, an additional air inlet opening into said outlet chamber, and formed by a central passage through 5 said rear body part and the directing cone.

11. A spraying nozzle or atomizer comprising the combination of disc like front and rear body parts secured together and recessed on their meeting faces to form between them a central outlet chamber and an annular fluid supply chamber divided from said central outlet chamber by an annular partition, an annular fluid supply chamber formed by a recess in the rear body part, a directing cone formed on the face of said rear body part and located in the centre of the outlet chamber, tangentially arranged fluid passages formed in the said rear body part and through the annular 10 partition between the annular supply chamber and the outlet chamber, said passages in the rear body part and in the annular partition being inclined in converging directions, whereby the fluids from the respective supply 15 chambers are directed in tangential and converging directions into said outlet chamber about the directing cone, a forwardly projecting rim located on the face of the rear body part around the directing cone. 20 and between the outlets from the respective series of fluid supply passages, an additional air inlet opening into said outlet chamber and formed by a central passage through said rear body part and the directing cone.

12. A spraying nozzle or atomizer comprising the combination of disc like front and rear body parts secured together and recessed on their meeting faces to form between them a central outlet chamber, and an annular fluid supply chamber divided from said central outlet chamber by an annular partition, an annular fluid supply chamber formed by a recess in the rear body part, a directing cone formed on the face of said rear body part and located in the centre of the outlet chamber, tangentially arranged fluid passages formed in the said rear body part and through the annular partition between the annular supply chamber and the outlet chamber, said passages in the rear body part and in the annular partition being inclined in converging directions, whereby the fluids from the respective supply 45 chambers are directed in tangential and converging directions into said outlet chamber about the directing cone, an additional air inlet opening into said outlet chamber and formed by a central passage through said rear body part and the directing cone, an auxiliary air admission chamber provided with auxiliary air admission passages and comprised by an enlarged chamber located beyond the discharge nozzle of the said central outlet chamber and provided with a 50

discharge opening in alignment therewith.

13. A spraying nozzle or atomizer comprising the combination of disc like front and rear body parts secured together and recessed on their meeting faces to form between them a central outlet chamber, and an annular fluid supply chamber divided from said central outlet chamber by an annular partition, an annular fluid supply chamber formed by a recess in the rear body part, a directing cone formed on the face of said rear body part and located in the centre of the outlet chamber, tangentially arranged fluid passages formed in the said rear body part and through the annular partition between the annular supply chamber and the outlet chamber, said passages in the rear body part and in the annular partition being inclined in converging directions, whereby the fluids from the respective supply 70 chambers are directed in tangential and converging directions into said outlet chamber about the directing cone, an additional air inlet opening into said outlet chamber and formed by a central passage through said 75 rear body part and the directing cone, an auxiliary air admission chamber of curved internal formation provided with inclined and forwardly directed air inlet passages in its walls and forming an enlarged extension 80 of the nozzle of the outlet chamber, said auxiliary air admission chamber being provided with a discharge opening in alignment with said nozzle outlet.

14. A spraying nozzle or atomizer comprising the combination of disc like front and rear body parts secured together and recessed on their meeting faces to form between them a central outlet chamber, and an annular fluid supply chamber divided from said central outlet chamber by an annular partition, an annular fluid supply chamber formed by a recess in the rear body part, a directing cone formed on the face of said rear body part and located in the centre of the outlet chamber, tangentially arranged fluid passages formed in the said rear body part and through the annular partition between the annular supply chamber and the outlet chamber, said passages in the rear body part and in the annular partition being inclined in converging directions, whereby the fluids from the respective supply 100 chambers are directed in tangential and converging directions into said outlet chamber about the directing cone, an additional air inlet opening into said outlet chamber and formed by a central passage through said rear body part and the directing cone, a plug for closing the additional central air 105 passage when required.

15. A spraying nozzle or atomizer comprising the combination of disc like front and rear body parts secured together and recessed on their meeting faces to form be-

tween them a central outlet chamber, and an annular fluid supply chamber divided from said central outlet chamber by an annular partition, an annular fluid supply chamber 5 formed by a recess in the rear body part, a directing cone formed on the face of said rear body part and located in the centre of the outlet chamber, tangentially arranged fluid passages formed in the said rear body 10 part and through the annular partition between the annular supply chamber and the outlet chamber, said passages in the rear

body part and in the annular partition being inclined in converging directions, whereby the fluids from the respective supply 15 chambers are directed in tangential and converging directions into said outlet chamber about the directing cone, screwed inlet passages to the respective fluid feeding chambers, whereby the atomizer formed by 20 said disc like body parts may be connected to and supported upon the pipes which supply the fluids.

HERBERT ALEXANDER THOMPSON.
